(P.O. Box 101, Millbrae, Calif.)

Filed May 18, 1959, Ser. No. 55,942

Term of patent 14 years

(Cl. D16—2)

FIG. 1

FIG. 2

FIG. 3

FIG. 4

FIG. 5

FIG. 6

Fig. 1 is a front perspective view of the mobile laboratory table and cabinet unit on a slightly reduced scale, showing my new design;

Fig. 2 is a front elevational view thereof;

Fig. 3 is a left side elevational view thereof;

Fig. 4 is a top plan view thereof;

Fig. 5 is a fragmentary perspective view thereof showing the hot plate on an enlarged scale; and

Fig. 6 is a fragmentary perspective view thereof showing one of the drawer handles on an enlarged scale.

The rear is substantially the same as the front, but without the drawer and drawer handles and the right is substantially the same as the left side, but without electrical outlets.

I claim:

The ornamental design for a mobile laboratory table and cabinet unit, as shown and described.
